BATTISTA CORTESE, OF NEW YORK, N. Y.

SPONGING-MACHINE.

1,310,325.

Specification of Letters Patent. Patented July 15, 1919.

Application filed September 6, 1918. Serial No. 252,945.

To all whom it may concern:

Be it known that I, BATTISTA CORTESE, a subject of the King of Italy, and a resident of the city of New York, borough of Manhattan, in the county and State of New York, have invented a new and Improved Sponging-Machine, of which the following is a full, clear, and exact description.

This invention relates to means for operating or controlling the actuation of the rolls for the steam sponging of cloth.

In the usual practice of these machines the rolls are operated by hand through cranks or wheels, a practice that is exceedingly laborious, and requires a vast amount of time. Furthermore the cloth itself is not so well cared for as in the practice of my improvement. By my improvement, therefore, I provide a motor, or its equivalent, for mechanically operating the rolls at any desired or variable speeds, and in either direction whereby the work may be performed both expeditiously, and in the best interests of the fabric.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation indicating the arrangement and location of the principal parts of my improvement.

Fig. 2 is a sectional detail on the line 2—2 of Fig. 1.

Fig. 3 is a similar view on the line 3—3.

Fig. 4 is a horizontal section on the line 4—4; and

Fig. 5 is a detail section on the line 5—5 of Fig. 3.

Referring now more specifically to the drawings, I show at 10 and 11 the main large steam rolls journaled in bearings 12 at the top of the main frame 13 with their axes in substantially the same horizontal plane. These rolls ordinarily are of the same diameter and of any suitable length to accommodate the greatest widths of cloth. Spaced rearwardly from the intermediate roll 11 is a final cloth receiving roll 14 journaled in bearings 15 on the same frame

and preferably at the same level. In front of the first steam roll 10 are one or more preliminary rolls 16 over or from which the cloth is rolled to the first steam roll. The general arrangement of the rolls is not new, but the same is referred to as a basis for my improved operating and controlling mechanism.

M is a motor located in any convenient place as within the main frame 13 and below the roll 14. Associated with this motor is a speed controller 17, a main switch 18, and pole changer 19, all shown as located upon a switchboard 20 in convenient reach of the operator adjacent to the primary steam roll.

At 21 I indicate a frame extension. Back of this extension and beneath the steam rolls is arranged any suitable form of base 22 having or supporting a series of three bearings 23, 24, and 25 in which are journaled a like number of shafts 26, 27, and 28 respectively all parallel to one another and preferably in the same horizontal plane, the front ends of these shafts being journaled in bearings 29, 30, and 31 respectively fitted in the frame extension 21. The shaft 28 is longer than either of the other two shafts and has fitted to its rear or inner end a power transmitting member shown in the form of a pulley 32 over which a belt 33, or its equivalent, operates from a motor pulley 34. Thus the shaft 28 is rotated at relatively high speed almost directly from the motor.

A pinion 35 fixed to the shaft 28 meshes with and drives a large gear 36 fixed to the intermediate shaft 27 whereby this shaft is driven at a much lower speed than the shaft 28. A pair of gears 37 and 38 are connected to the respective shafts 27 and 26 and mesh constantly with each other. These gears being fixed to the shafts and of the same diameter, the shaft 26 is thereby driven at the same speed as the shaft 27, but in a different direction.

Below the shaft 10' of the roll 10 is a jack shaft 39 having on its front end a small pinion 40 meshing with a gear 41 fixed to the shaft 10'. On the rear end of the jack shaft back of or within the frame 13 is a sprocket wheel 42 over which a chain 43, or its equivalent, operates from a sprocket wheel 44 carried by a clutch cone 45 fitted loosely and sildably on the shaft 26 and adapted to coöperate with a clutch

cup 46 constituting a part of the gear 38 fixed to said shaft 26. A spring 47 lying within the cup tends to hold the cone spaced therefrom. This cone, however, is adapted 5 to be forced forward into frictional engagement with the cup 46 by means of a bell crank lever 48 pivoted at 49 and having at its front end a pedal 50, while at its upper rear end is a yoke 51 having anti-friction 10 rollers 52 bearing against the rear end of the cone. The weight of the pedal 50 holds the rollers 52 normally in easy contact with the rear end of the cone 45 so that there is no lost motion with respect to the clutch 15 setting mechanism when the operator puts his foot on the pedal. In order to reduce as much as possible all sliding friction between the rollers and the member 45, said rollers 52 are preferably conical in form and co- 20 operate with a flat conical rear end of the cone member 45. The pedal 50 projects from the front of the machine beyond the auxiliary frame 21. It will be understood that when the motor is running all of the 25 shafts 26, 27, and 28 are also running. With respect to the operation of the roll 10 on which the cloth is first wound it is frequently necessary for the operator to stand at different places, as for example at the front 30 of the machine or at the side adjacent to the rolls 16. Hence, I provide an auxiliary pedal 53 pivoted at 54 and acting through an intermediate lever 55 pivoted at 56 whereby the bell crank 48 may be actuated conveniently from either pedal 50 or 53, and when 35 it is so actuated the cone 45 is forced into frictional engagement with the cup or hub of the gear 38 causing rotation of the roll 10 at relatively low speed.

40 The hub of the gear 37 is similar to that of the gear 38 and hence consists of a clutch cup 57 with which the clutch cone 58 is caused to frictionally engage through the actuation of a bell crank 59 having at its 45 front end a pedal 60, and at its rear end a yoke 61 having anti-friction rollers 62 bearing against the rear end of the cone 58. This cone carries a sprocket wheel 63 through which a chain 64 operates to and 50 around a sprocket wheel 65 connected to the rear end of a jack shaft 66 on the front end of which is fixed a pinion 67 meshing with a gear 68 on the front end of the shaft 11' of the intermediate roll 11. As shown the 55 gears 44 and 63 are of the same diameter, but the upper gear 65 is materially smaller than the corresponding gear 42. Therefore, since the shafts 26 and 27 operate at the same speed and the chains 43 and 64 are 60 driven therefrom at equal speeds the disparity between the gears 65 and 42 provides that the roll 11 is operated at a materially higher speed than the primary roll 10. In the practice of the invention after a sufficient 65 quantity of the cloth is rolled upon the roll

10 it, or a portion of it, is then rolled upon the secondary roll from the first roll. Steam is then applied to either or both of the rolls at any desired time according to the nature of the cloth or requirements in practice, the 70 nature of the operating means for the rolls serving to facilitate the rolling action and to insure that the steam will be applied uniformly throughout the roll or bolt of cloth.

After the cloth is steamed or treated on 75 the rolls 10 and 11 as above set forth it is transferred quickly to the final roll 14, the operation of which is effected or controlled by means of a clutch comprising relatively fixed and movable members 69 and 70 on 80 the shaft 28. The clutch member 69 has a hub on which is fixed a sprocket wheel 71 over which a chain 72 operates to a corresponding wheel 73 fixed to the front end of the shaft 14' of the final roll. A spring 74 85 acts to normally keep the clutch members separated as shown in Fig. 5, but a bell crank 75 pivoted at 76 and having at its front end a pedal 77 and at its upper end a yoke 78 with anti-friction rollers 79, acts 90 to move the movable clutch member into frictional engagement with the fixed member 69 whereby the roll 14 will be driven at relatively high speed from the high speed shaft 28. With the cloth rolled in this manner quickly upon the final roll 14, this roll may be removed from the machine with the cloth thereon and another substituted to receive the roll of cloth next to be treated by the apparatus.

100 I claim:

1. In a sponging machine, the combination with primary and secondary steam rolls, of power means to control the operation thereof, said power means comprising a pair of 105 parallel shafts, means to rotate the shafts at the same speed in opposite directions, gear connections between the respective rolls and said shafts, and means to selectively operate either of said gear connections from a selected shaft, said gear connections providing for rotation of one of the rolls at a higher speed than the other.

2. In a sponging machine, the combination with primary and secondary steam 115 rolls, and means to deliver a bolt of cloth thereto and therefrom, of means to control the operation of said rolls, said controlling means including a pair of parallel shafts, means to rotate both of the shafts simultaneously in opposite directions at relatively high speed, and independent gear connections between the shafts and the respective rolls, said connections including foot operated clutches, one of said gear connections 120 providing for the rotation of one of the rolls at higher speed than the other.

3. In a sponging machine, the combination with primary and secondary steam rolls, and means to deliver a bolt of cloth 130

thereto and therefrom, of means to control the rotation of said rolls, said controlling means including a pair of parallel shafts journaled in the same plane below the plane 5 of the rolls, means to rotate one of the shafts, a pair of gears of equal size fixed to the shafts whereby one is driven from the other at the same speed, a pair of clutches mounted on the respective shafts and coöperating with the hubs of said gears, said clutches carrying a pair of sprocket wheels, a pair of sprocket chains operating over said sprocket wheels, means to selectively set one or the other of said clutches where- 10 by the corresponding chain is driven, and gear connections between said chains and the respective rolls whereby either desired roll is operated.

4. In a sponging machine, the combination 20 with a series of rolls journaled for rotation in substantially the same plane, and means to deliver a bolt of cloth to the first roll of the series, of means to control the rotation of any of the rolls in either direction, said controlling means including a motor, a series of parallel shafts journaled in the same plane below the plane aforesaid, driving means between the motor and one of said shafts for rotation thereof at 25 high speed, gear connections between the last mentioned shaft and the other shafts of the series whereby said others are rotated at the same speed, but at a lower speed than the driving shaft, a series of clutches 30 mounted on the respective shafts, and a series of sprocket chain connections between said clutches and the several rolls.

5. In a sponging machine, the combination 40 with a primary steam roll, a frame supporting the same, and roller means to deliver cloth to and from said steam roll, of means to control the rotation of the steam roll, said controlling means including a shaft journaled below the roll, power means 45 to rotate the shaft, a clutch mounted upon the shaft, one member of the clutch being connected to the shaft and the other member of the clutch being movably related thereto, gear connections between the movable clutch member and the steam roll, and means to set the clutch, said clutch setting means being accessible for operation by the operator's foot at either the front or side of said frame.

55 6. In a sponging machine, the combination 50 with a primary steam roll, a frame supporting the same, and roller means to deliver cloth to and from said steam roll, of means to control the rotation of the steam roll, said controlling means including a shaft journaled below the roll, power means

to rotate the shaft, a clutch mounted upon the shaft, one member of the clutch being connected to the shaft and the other member of the clutch being movably related 65 thereto, gear connections between the movable clutch member and the steam roll, and means to set the clutch, said clutch setting means comprising a bell crank lever having a pedal at one end and an auxiliary pedal 70 operating on said bell crank in a plane at right angles to the first mentioned pedal.

7. In a sponging machine, the combination 75 with a steam roll, and means to deliver a bolt of cloth thereto and therefrom, of means to control the rotation of said roll, said controlling means including a shaft parallel to the axis of the roll, power means to operate the shaft in either direction, a clutch member fixed to the shaft, a 80 clutch member mounted loosely and slidably upon the shaft, a gear mounted upon the slideable clutch member, gear connections between said clutch gear and the roll, and means to operate the clutch, said clutch operating means including a bell crank pivoted below the shaft and having on one end a pedal and on the other end an up- 85 standing yoke extending to opposite sides of the shaft, and a pair of rollers journaled 90 upon the ends of the yoke and having constant rolling contact by virtue of the weight of the pedal with the end of the slideable clutch member, said rollers being coaxial and perpendicular to the axis of the shaft. 95

8. In a sponging machine, the combination 100 with a steam roll, and means to deliver a bolt of cloth thereto and therefrom, of means to control the rotation of said roll, said controlling means including a shaft parallel to the axis of the roll, power means to operate the shaft in either direction, a clutch member fixed to the shaft, a clutch member mounted loosely and slidably upon the shaft, a gear mounted upon the slideable 105 clutch member, gear connections between said clutch gear and the roll, and means to operate the clutch, said clutch operating means including a bell crank lever pivoted below the shaft and having an arm projecting forward terminating in a foot pedal and having its other arm consisting of a yoke extending upward on opposite sides of the shaft, anti-friction rollers journaled upon the arms of the yoke in the same horizontal plane as the axis of the shaft and having constant rolling contact with a slideable clutch member, and auxiliary pedal devices pivoted for actuation of said bell crank in a plane perpendicular to the plane 110 of the bell crank. 115

BATTISTA CORTESE.
